LOREN G. SYMONS, OF HOLLYWOOD, CALIFORNIA, ASSIGNOR TO THOMAS L. MORRIS,
OF VAN NUYS, CALIFORNIA

ROTARY FLUID PUMP

Application filed December 26, 1928. Serial No. 328,349.

My invention relates to an improvement in rotary pumps and in particular to an improvement in the type of rotary pump in which a pumping screw or worm is rotated in mesh with a grate member which prevents the rotation with the rotor of the fluid being pumped. One object is the provision of a helically vaned rotor and a gate meshing and in closing engagement with the rotor so that leakage of the pump shall be maintained at a minimum.

Another object is to provide a novel and effective form of gate composed of relatively movable members having alternating teeth thereon for engagement with the helical vane of the rotor and formed for close engagement so as to close the cylinder at the points of engagement against leakage.

Other objects will appear from time to time in the course of the specification and claims.

I illustrate my invention more or less diagrammatically in the accompanying drawings, wherein:

Fig. 1 is a transverse section of a pump embodying my improvements.

Fig. 2 is a face view of one of the gate members.

Fig. 3 is a section of the same on the line 3-3 of Fig. 2.

Fig. 4 is a plan view of another of the gate members.

Fig. 5 is a section of the same on the line 5-5 of Fig. 4.

Fig. 6 is a sectional plan of the pump on a reduced scale on line 6-6 of Fig. 1.

Fig. 7 is a view of the rotor and gate in operative engagement.

Fig. 8 is a section of the same on line 8-8 of Fig. 7.

Fig. 9 is another view of the rotor and gate engaged at different relative positions from Fig. 7.

Fig. 10 is a section of the same on the line 10-10 of Fig. 9.

A indicates any suitable base or supporting member upon which the pump housing A1 is mounted, and may include supporting portions A2 having feet A3 secured to the member A by means of bolts A4.

The pump cylinder B may be mounted or

formed on the portion A2 of the pump frame, and provided with an intake manifold B1 in connection with an inlet passage B2, as shown in Figure 6, and provided with inlet ports B4, B4, at the ends, for affording communication with the interior of the cylinder B.

C indicates an outlet passage, shown in Figure 6 as intermediate the ends of the cylinder and communicating with the chamber C1 and thus with an outlet duct C2.

The pump rotor includes the shaft ends D1 and D2 which rotate in the bearings D3, D3 at the ends of cylinder B. Said bearings are mounted in bosses D4, D4 which extend inwardly from the ends of the cylinder chamber.

The rotor body D5 engages the opposed faces of the bearings D3, D3 at its ends. Any suitable means may be employed for rotating the rotor, as for example a train of gears, not herein shown, associated with the shaft D2 and driven by any suitable motive power, not herein shown.

The enlarged body D5 of the rotor has two vanes E and E1 of opposite pitch formed on its periphery. One is positioned on each side of the outlet passage C, whereby their thrust will balance and prevent any axial end thrust along the axis of rotation of the rotor. The worms E and E1 are identical except that one is right and the other is left hand, and the gates cooperating with the worms are identical, although rotating in opposite directions. Only one of the worms and one of the gates will be described in detail. The worms are of generally uniform height and thickness from end to end, save for a relatively short tapered portion E2 at each end. It will be understood that the end of the worm terminates along a plane generally radial in relation to the axis of rotation of the rotor. The body D5 of the rotor is of identical diameter from end to end.

Each vane or worm meshes with a gate as at G, and the gates G, G are positioned at opposite sides of the pump housing. Each such gate includes two relatively movable members, shown in detail in Figures 2 to 5 inclusive. One of these members has a web

G1 with a central aperture G2. Formed on the periphery of the web and perpendicular thereto, are a plurality of arcuate lugs G3. Projecting from each such lug, and still perpendicular to the plane of the web G1 are teeth G4. These teeth are rounded on opposite facets and the opposed facets G5 of each tooth are concentric, while the opposite facets G6 are concentric with the axis of the gate.

A second gate member G7 is provided on its periphery with radial lugs G8 of the same thickness and radius as the lugs G3 and terminating at the same distance from the tops of the gate teeth. Projecting from each of said lugs G8 are teeth G9 identical with the teeth G4. When the member G7 is placed within the member G1 and its aperture G10 alined with the aperture G2, the distance between the opposed end faces of the lugs G3 and G8 is such as to permit a certain degree of relative rotation of the two members and of their respective teeth.

The entire gate assembly so formed is inserted within a gate housing H, integral with the pump frame, which includes a channel H1 adapted snugly to receive the teeth G4 and G9. This channel intersects the interior of the pump cylinder B in such fashion that at one point in their rotation the teeth G4 and G9 project into the interior of the pump chamber to the extent of their entire height and closely engage the opposed surface of the rotor member D5 and mesh with the worms E and E1. The gate members are held in position by a plug H2 which has a central boss H3 seating in the apertures G2 and G10. Rotation of member H2 is prevented for example by a pin H4 one portion of which seats in the pump frame and the other in the boss H3 which is apertured to receive it. A plug H5 may be screwed into the portion H for enclosing each of the gates and for affording access thereto when and if necessary.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

One of the great problems in the successful use of rotary pumps of the general type herein described, and probably the major reason why such pumps have not gone into more general use, is the difficulty in constructing a gate with teeth which mesh with the worm of the rotor sufficiently tightly to prevent leakage.

Figures 8 and 10 will at the same time illustrate the difficulty and the solution. The distance between the opposed sides of each worm is identical from end to end of the worm except for the extreme tapered portions. Also, the thickness of the worm is uniform from end to end, save for the tapered portions. Finally, the depth of the thread so formed is uniform from end to end. But as the individual gates move in an arcuate path their longitudinal movement varies perceptibly in rate, whereas the longitudinal movement of the face of the worm, at any given point about the periphery of the cylindrical casing, is uniform. The result is that in order to make a gate which will mesh uniformly, and will uniformly close the space between the vanes, some means must be developed for compensating for this differential factor. My solution has been to permit individual and adjacent gate members a measure of relative movement.

Consider first Figures 7 and 8 and assume that the gate is moving in clockwise direction. The tooth or gate member indicated as "a" has moved into engagement with the outside of the thread, the teeth b and c are within the thread and the tooth d is about to move out of contact with the outside of the opposite end of the thread. Note that a, meeting the face of the thread at a substantial angle, is spaced apart from the tooth b by a considerably greater distance than the space separating b and c which may be described as lying along or generally parallel with the axis of the rotor. Similarly a greater distance separates c and d, which lie in an angular relation to the thread and rotor similar to that of a and b. Were the various gate members not removably mounted it is clear that they would either cramp in meshing with the thread, or would have to be made with greater clearance. If they cramp, they render the device inoperative. If they are made with greater clearances, they cause leakage. But when the teeth are made relatively movable one set moves toward and away from the other in such fashion as to compensate for the variation in the angular relation of the line of approach of any individual tooth to the opposed worm surface against which it moves.

Consider Figures 9 and 10 as showing a different position. The tooth a, having moved along the worm, now defines a more acute angle in relation to the axis. The tooth b may be described as parallel with the axis, and the tooth c lies at an angle equal to but reverse to that of the tooth a. Since angular relation between a and b is the same as that between c and b the teeth will be at the same distance from each other and note that in Figure 10 the individual teeth members are equally spaced about the gate, in

contrast to the unequal spacing or grouping of Figure 8.

I claim:

1. In a fluid pump, a rotor and a housing therefor, a fluid inlet to said housing and a fluid outlet from said housing, said rotor including a body portion and a helical vane thereon, a gate mounted for rotation about an axis perpendicular to the axis of rotation of the rotor, said gate including a plurality of teeth paralleling the axis of the gate and adapted to mesh with said vane and means for permitting relative movement of said teeth in relation to each other. 10
2. In a fluid pump, a rotor and a housing therefor, a fluid inlet to said housing and a fluid outlet from said housing, said rotor including a body portion and a helical vane thereon, a gate mounted for rotation about an axis perpendicular to the axis of rotation of the rotor, said gate including a plurality of sets of teeth paralleling the axis of the gate and adapted to mesh with said vane and means for permitting relative movement of said sets of teeth in relation to each other. 20
3. In a fluid pump, a rotor and a housing therefor, a fluid inlet to said housing and a fluid outlet from said housing, said rotor having a helical vane thereon, a gate mounted for rotation about an axis perpendicular to the axis of rotation of the rotor, said gate including a plurality of sets of teeth paralleling the axis of the gate and adapted to mesh with said vane and means for permitting relative movement of said sets of teeth in relation to each other, said sets being arranged with the teeth of each set alternating about said gate. 30
4. In a fluid pump, a rotor and a housing therefor, a fluid inlet to said housing and a fluid outlet therefrom, said rotor including a body portion and a helical vane thereon, said vane constituting a worm, the thickness of said worm being uniform throughout substantially the entire length of the worm, the separation between opposed walls of the worm being substantially uniform from end to end of the worm, a gate mounted for rotation about an axis perpendicular to the axis of rotation of the rotor, said gate including a plurality of teeth paralleling the axis of the gate and adapted to mesh with said worm, and means for permitting movement of said teeth in relation to said gate member. 40
5. In a fluid pump, a rotor and a pump chamber in which said rotor rotates, a fluid inlet to said chamber and a fluid outlet therefrom, said rotor including a helical worm, a gate mounted for rotation about an axis perpendicular to the axis of rotation of the rotor, said gate including a plurality of teeth paralleling the axis of the gate and adapted to mesh with said worm, and means for permitting relative movement of adjacent teeth in relation to each other. 50
6. In a fluid pump, a rotor and a pump chamber in which said rotor rotates, a fluid inlet to said chamber and a fluid outlet therefrom, said rotor including a helical worm, a gate member mounted for rotation about an axis perpendicular to the axis of rotation of the rotor, said gate including a plurality of teeth paralleling the axis of the gate and adapted to mesh with said worm, and means for permitting relative movement of adjacent teeth in relation to each other, said gate including two associated rotary base portions the said teeth being distributed between said portions, the two portions being relatively movable. 60
7. In a fluid pump, a rotor and a pump chamber in which said rotor rotates, a fluid inlet to said chamber and a fluid outlet therefrom, said rotor including a helical worm, a gate mounted for rotation about an axis perpendicular to the axis of rotation of the rotor, said gate including a plurality of teeth paralleling the axis of the gate and adapted to mesh with said worm, and means for permitting relative movement of adjacent teeth in relation to each other, said gate including two associated rotary members having said teeth distributed between said members, the two members being relatively movable, the teeth being arranged to alternate on the two members. 70
8. In a fluid pump, a rotor and a housing therefor, a fluid inlet to the housing, a fluid outlet from the housing, the rotor including a body portion and a helical vane thereon, a composite gate mounted for rotation about an axis perpendicular to the axis of rotation of the rotor and including telescoping body portions with alternating teeth arranged in the same operative plane and adapted to mesh with said vane, and means for permitting relative movement of said body portions for automatically adjusting the teeth for contact with said vane. 80
9. In a fluid pump, a rotor and a housing therefor, a fluid inlet to the housing, a fluid outlet from the housing, the rotor including a body portion and a helical vane thereon, a composite gate mounted for rotation about an axis perpendicular to the axis of rotation of the rotor and including telescoping body portions with alternating teeth arranged in the same operative plane and adapted to mesh with said vane, and means for permitting relative movement of said body portions for automatically adjusting the teeth for contact with said vane, said teeth having inner and outer faces concentric with the axis of the gate, for the purpose described. 90
10. In a fluid pump, a rotor and a housing therefor, a fluid inlet to the housing, a fluid outlet from the housing, the rotor including a body portion and a helical vane thereon, a composite gate mounted for rotation about an axis perpendicular to the axis of rotation of the rotor and including telescoping body portions with alternating teeth arranged in the same operative plane and adapted to mesh with said vane, and means for permitting relative movement of said body portions for automatically adjusting the teeth for contact with said vane, said teeth having inner and outer faces concentric with the axis of the gate, for the purpose described. 100

axis perpendicular to the axis of rotation of the rotor and including telescoping body portions with alternating teeth arranged in the same operative plane and adapted to mesh with said vane, means for permitting relative movement of said body portions for automatically adjusting the teeth for contact with said vane, said teeth having inner and outer facets concentric with the axis of the gate, and 10 opposite facets arcuately formed for frictional contact with said vane.

11. In a fluid pump, a rotor and a housing therefor, a fluid inlet to and a fluid outlet from said housing, said rotor including a 15 body portion and a helical vane thereon, a gate mounted for rotation about an axis perpendicular to the axis of rotation of the rotor, said gate including a pair of concentric members, one of said members nested concentrically 20 within the other member, said members having sets of teeth alternating with each other and adapted to mesh with said vane, and means for permitting relative movement of said teeth, for the purpose described.
